(57) **CLAIM**

The ornamental design for an ammunition side saddle, as shown and described.

DESCRIPTION

FIG. 1 is a front perspective view of an ammunition side saddle showing the new design;

FIG. 2 is a front view thereof;

FIG. 3 is a rear view thereof;

FIG. 4 is a side view thereof;

FIG. 5 is a side view thereof opposite that of FIG. 4;

FIG. 6 is a top view thereof;

FIG. 7 is a bottom view thereof;

FIG. 8 is another perspective view thereof shown in an environmental use configuration with two ammunition rounds; and,

FIG. 9 is another perspective view thereof showing shown in another environmental use configuration with two ammunition rounds and a firearm.

The broken lines depict portions of the ammunition side saddle that form no part of the claimed design. The additional broken lines in FIGS. 8 and 9 depict environment that form no part of the claimed design.

1 Claim, 6 Drawing Sheets
